US0D1058078S

(12) **United States Design Patent** (10) **Patent No.:** **US D1,058,078 S**
(45) **Date of Patent:** **** Jan. 14, 2025**

(54) **SWEEPING ROBOT**

(71) Applicant: **Shenzhen Apeman Innovations Technology Co., Ltd.**, Guangdong (CN)

(72) Inventors: **Tingyuan Luo**, Shenzhen (CN); **Sasha Tseng**, Guangdong (CN); **Chiawei Lin**, Guangdong (CN); **Jianan Zhao**, Guangdong (CN); **Jiawen Jiang**, Guangdong (CN)

(**) Term: **15 Years**

(21) Appl. No.: **29/887,070**

(22) Filed: **Mar. 16, 2023**

(30) **Foreign Application Priority Data**

Nov. 14, 2022 (CN) 202230756644.9

(57) **CLAIM**

The ornamental design for a sweeping robot, as shown and described.

DESCRIPTION

FIG. 1 is a top, front, right side perspective view of a sweeping robot, showing our new design;
FIG. 2 is a top, rear, left side perspective view thereof;
FIG. 3 is a bottom, rear, right side perspective view thereof;
FIG. 4 is a front view thereof;
FIG. 5 is a rear view thereof;
FIG. 6 is a left side view thereof;
FIG. 7 is a right side view thereof;
FIG. 8 is a top view thereof;
FIG. 9 is a bottom view thereof;
FIG. 10 is an exploded view of the sweeping robot, which is the charging part as the sweeping robot; and,
FIG. 11 is an exploded view of the sweeping robot, which is the main body as the sweeping robot.
The broken lines in the drawings depict portions of the sweeping robot that form no part of the claimed design.

1 Claim, 11 Drawing Sheets
